DRAINING APPARATUS

Ervin J. Kolvers, Milwaukee, Wis., assignor to Allis-Chalmers Manufacturing Company, Milwaukee, Wis.

Filed Oct. 6, 1961, Ser. No. 143,433

4 Claims. (Cl. 165—47)

This invention relates to apparatus for draining heat transfer liquid from cooling systems.

In operations that produce heat either as an inherent goal or as a byproduct of friction losses (for example, furnaces produce heat as an inherent characteristic of their operation and bearings produce heat from the friction created between surfaces) where the heat produced is not directly utilized or channeled, it is usually necessary to cool the heat producing structure. This is often accomplished by circulating a heat transfer liquid, such as water, around the heat producing portion by having the immediate structural components cored to form a chamber for circulating the heat transfer (cooling) liquid. This cored section or chamber is liquid tight and has an inlet for admission and an outlet for discharge of cooling liquid. In addition, it is advantageous, and sometimes necessary, to provide an arrangement for completely draining the chamber when the unit is not operating. This arrangement is normally separately located from the inlet and outlet when neither the inlet nor the outlet are located at a low portion of the chamber.

Water is the most commonly used heat transfer liquid because it is generally inexpensive and readily available in most areas. However, since water freezes at temperatures that are encountered in many areas of application it is necessary to provide a means for draining the chamber when the unit is not operating and the ambient temperature becomes lower than its freezing point. It is, of course, possible to add substances to water to lower its freezing point but this is not practical or feasible in many situations. In addition, it is desirable to be able to easily drain a system and chamber for maintenance purposes or when long shut down periods are encountered.

The most common manner of draining the chamber utilizes a drain opening and plug located at a low point in the chamber. This drain plug is removed (or opened if it is a valved drain) whenever it is desirable to drain the chamber. In some systems this drain opening need only pass through a single wall, the wall of the chamber, in order to communicate between the chamber and the atmosphere. In this situation there are usually no difficulties encountered, outside of possible inconvenience, in draining the system. In other situations, however, the drain, if it is to be located at a lower portion of the chamber, must open into a pipe which passes through supporting structural components before it reaches the atmosphere. This type of structure raises difficulties both in construction and maintenance. And where the supporting structure contains fluid compartments, such as oil reservoirs for containing lubricant, there is the further problem of preventing leakage along the outside of the drain pipe. Also, there is the necessity of not restricting a small amount of motion between the cored chamber and the supporting structure. The cored chamber, being a bearing, must be free to align itself with the shaft. Past experience has shown that where this situation exists, there is a great likelihood of oil leaking along this pipe out of the reservoir. This loss of oil is uneconomical and could result in serious damage to the lubricated surfaces if the oil level should drop below that required for proper lubrication.

An example of an apparatus that has such an arrangement is a trunnion supported grinding mill which contains a cored bearing shell enclosing a chamber for the circulation of cooling liquid and an oil reservoir in the sup-

2

porting structure below the chamber. In this particular type of application the oil leakage problem has significance and attempts to solve the problem by proper sealing along the drain pipe have not been entirely successful.

In this invention the drain pipe connections are made at a higher portion of the chamber so that it is not necessary for the drain pipe to pass through the supporting structure located beneath the chamber. Particularly, it is possible to avoid passing the drain pipe through the oil reservoir which is normally located beneath the chamber in trunnion bearing shell or similar apparatus. Since the inlet and outlet connections for circulation during cooling are located at higher levels in such a chamber there is usually no difficulty in communicating directly from the chamber, through the upper chamber wall, and into conduits normally communicating with the atmosphere. This invention accomplishes draining from a lower level of the chamber to outlet connections located at a higher level by using an internal syphon tube or similar draining means, located within the chamber, for carrying liquid from a lower level of the chamber to the outlet. Thus, there are no external connections at the lower level of the chamber but only at higher levels located at or near the usual inlet and outlet connections. The means utilized in forcing the flow of liquid from the chamber to the outlet when the flow of the cooling liquid into the chamber is stopped can be either pressurized gas introduced to cause the discharge of the liquid or atmospheric air to allow syphoning to take place from the chamber to an outlet.

The objects of this invention include providing a new and improved arrangement for draining the chamber of a circulatory cooling system capable of simple, convenient, and practical operation that eliminates the need of passing a drain pipe through supporting structure beneath the chamber, thereby avoiding passing a drain pipe through a fluid tight compartment such as an oil reservoir and avoiding hindering the free motion of the bearing shell in relation to the supporting structure.

Other objects and advantages of this apparatus and the operation thereof will be evident from the following detailed description and explanation.

FIG. 1 is a partially cut away view of a trunnion supported grinding mill with a cored bearing shell that embodies this invention;

FIG. 2 is a cross sectional end view of the semiannular cooling fluid chamber shown in FIG. 1 with valves in position for conducting cooling fluid through the chamber;

FIG. 3 is the same end view as that shown in FIG. 2 with the valves in position for draining the chamber; and FIG. 4 is a portion of the same end view.

Referring to FIG. 1, a revolvable cylinder 1 has a trunnion 2 resting upon a trunnion bearing surface 3. Trunnion bearing surface 3 is part of a cored bearing shell 10 disposed upon supporting structure 9, which also contains and defines a semiannular chamber 11 located adjacent to the trunnion bearing surface and an oil reservoir 4 located in the supporting structure 9 below the cored bearing shell. The entire trunnion, supporting structure, and bearing shell are housed within a cover assembly 5 which consists, in part, of a cover wall 6. An inlet valve control 7 extends through cover wall 6 and connects to an inlet valve (not shown in FIG. 1) that will be described later and a discharge valve control 8 connects to a discharge valve 25 that will also be described later.

Referring to FIG. 2, cored bearing shell 10 defines semiannular chamber 11. At one apex of the semiannular chamber an inlet valve 12 has a first inlet valve port 13, second inlet valve port 14, and third inlet valve port 15.

Inlet valve 12 connects to semiannular chamber 11 by means of an inlet conduit 18 and inlet port 19. With the inlet valve in the position shown in FIG. 2, a liquid inlet means 16 is created and consists of such as a liquid conduit 17, inlet valve 12 (through its second inlet valve port 14 and its first inlet valve port 13), inlet conduit 18, and inlet port 19.

A gas conduit 23, as shown in FIG. 2, is shut off by the valving effect of inlet valve 12 which is shown blocking its third inlet valve port 15. The purpose of this conduit 23 will appear as the description of the invention proceeds with later reference to other figures in the drawing.

With continued reference to FIG. 2, a discharge valve 25 can be seen at the opposite end of semiannular chamber 11. Discharge valve 25 has a first discharge valve port 26, second discharge valve port 27, and third discharge valve port 28 and is in communication by its first discharge valve port 26 with the semiannular chamber through an outlet means 30 which consists of such as an outlet port 31 and outlet conduit 32. With discharge valve 25 in the position shown in FIG. 2, the semiannular chamber communicates to a discharge means 35 which consists of such as a discharge conduit 36 (connected to second discharge valve port 27) and discharge outlet 37. Also communicating with discharge valve 25 at its third discharge valve port 28 is a draining means 40 which consists of such as a draining conduit 41 (connected to third discharge valve port 28) and a draining tube 42 with a draining port 43. With the discharge valve in the position shown in FIG. 2, draining means 40 is shut off by discharge valve 25 blocking off third discharge valve port 28.

Referring to FIG. 3, the inlet valve 12 is shown in a position that defines a gas inlet means 22 which consists of such as gas conduit 23, inlet valve 12 (through its third inlet valve port 15 and its first inlet valve port 13), inlet conduit 18, and inlet port 19. At the opposite end of semiannular chamber 11, discharge valve 25 is shown in a position that allows communication between draining means 40 and discharge means 35 via its third discharge valve port 28 and its second discharge valve port 27.

In the operation of the apparatus the inlet and discharge valves are placed in the position shown in FIG. 2 to provide for a flow of the liquid through chamber 11. With the valves in this position a liquid which may be cooling water flows along a path indicated by the solid arrows 20, through liquid inlet means 16 (i.e., 17, 14, 12, 13 and 18) into chamber 11. After flowing through the chamber, the liquid flows through outlet means 30 (i.e., 31, 32 and 26). With discharge valve 25 in the indicated position, liquid flows from outlet means 30 into discharge valve 25 and out through discharge means 35 (i.e., 27, 36 and 37).

Inlet port 19 and outlet port 31 are shown in their most advantageous location, that is, a location that gives a flow path straight through the chamber thereby eliminating any cavitation or eddying within the chamber that might create lesser heat transfer at these points and resulting hot spots in the chamber wall and adjacent portions of the bearing surface 3. Discharge outlet 37 may connect to a waste drain or it may connect to an arrangement for carrying the discharged liquid to a separate heat exchanger for cooling and recirculation into the chamber.

When the associated machinery is shut down and/or conditions are expected that require draining of chamber 11 the inlet and discharge valves may be placed in the position shown in FIG. 3 by turning the inlet valve control 7 and the discharge valve control 8 (both shown in FIG. 1) at substantially the same time. Upon turning inlet valve 12 to the position shown in FIG. 3, the valve communicates between third inlet valve port 15 and first inlet valve port 13 thereby creating the gas inlet means

22 (i.e., 23, 15, 12, 13, 18 and 19). With this inlet valve position, gas flows along a gas path shown by dotted arrows 24 through gas inlet means 22 into chamber 11.

With discharge valve 25 in the position shown in FIG. 3 the liquid remaining in the chamber is caused to flow, by the pressure of the gas introduced into the chamber at the inlet port 19, along a liquid flow path shown by solid arrows 20 (FIG. 3) through draining means 40 (i.e., 43, 42, 41 and 28) into discharge means 35 at second discharge valve port 27.

It is evident that liquid flows out of the chamber if the pressure of the gas within the chamber is greater than the pressure at discharge outlet 37. However, a simpler and preferred operation places discharge outlet 37 at atmospheric pressure at a point lower than draining port 43. With this arrangement atmospheric air is introduced into chamber 11 through gas inlet means 22, which now becomes a venting means, and syphoning takes place from chamber 11 at draining port 43 through a syphoning means consisting of draining means 40 and discharge means 35. The simplicity of the operation of turning the inlet and discharge valves makes the draining procedure very simple and convenient and therefore advantageous for this reason alone.

It is necessary, in order for syphoning to take place, that the liquid remaining in inlet conduit 18 displaces and forces any air entrapped in draining tube 42 and conduit 41 to a point in discharge conduit 36 that is below draining port 43. Normally, inlet conduit 18 will have sufficient height and volume so that if the valves are placed in the position shown in FIG. 3 (for syphoning) at substantially the same time the liquid remaining in the inlet conduit will be sufficient to displace any air that has accumulated in draining conduit 41 and draining tube 42. However, if the inlet valve is not located high enough or inlet conduit 18 has insufficient volume for this purpose, or it is not feasible to turn the valves at about the same time, it is possible to first briefly place discharge valve 25 in the position indicated in FIG. 4. This position would have to be maintained only long enough before the closing of liquid inlet means 16 to allow air entrapped in draining tube 42 and draining conduit 41 to be forced through discharge conduit 36. Another approach to accomplish the same thing in operation of the apparatus would be to turn the discharge valve to the position indicated in FIG. 3 before the inlet valve is turned (from normal operational flowing) to the position indicated in FIG. 3. With this arrangement, part of the liquid flows from inlet port 18 through draining port 43 and any entrapped air is forced out through draining means 40 into discharge means 35, thus filling the syphoning means with liquid and allowing syphoning action to take place when the inlet valve is turned to the syphoning position (shown in FIG. 3) for admitting atmospheric air to enter the chamber. The syphoning process then continues until the chamber is emptied.

It is apparent that the types, combinations, and placement of the conduits and valves, and the configuration of the chamber may be varied but still accomplish the same thing in substantially the same way. For example, it is possible to combine the valving operation by an appropriate connecting member, or to utilize separate on-off valves instead of the described valves. Therefore, the apparatus shown is illustrative only and is not intended to encompass all the possible variations of the invention.

Having now particularly described and ascertained the nature of my said invention and the manner in which it is to be performed, I declare that what I claim is:

1. An apparatus having a cored bearing shell describing a chamber extending between vertically spaced levels comprising: an inlet valve connecting and communicating with the chamber through an inlet port, said inlet port located at a higher of said levels of the chamber; a liquid conduit connecting to and communicating with the inlet valve; a gas conduit connecting to and communicating

with the inlet valve; an inlet valve control for rotating the inlet valve into two positions, the first position placing the liquid conduit in communication with the chamber, and the second position placing the gas conduit, inlet valve, inlet conduit, and inlet port in communication with the chamber; a discharge valve connecting and communicating with the chamber through an outlet port located at a higher of said levels of the chamber; a discharge conduit connecting and communicating with the discharge valve and having a discharge outlet disposed lower than said lower level of the chamber; a draining conduit connecting and communicating with the discharge valve disposed within the chamber and having a draining port located at a lower level of the chamber, said draining conduit passing through the shell at a higher of said levels of the chamber; a discharge valve control for rotating the discharge valve into two positions, the first position placing only the draining port in communication with the discharge conduit and the second position placing only the outlet port in communication with the discharge conduit.

2. An apparatus having a cored bearing shell describing a chamber extending between vertically spaced levels comprising: an inlet valve connecting and communicating with the discharge conduit with the chamber through an inlet port, said inlet port located at a higher of said levels of the chamber; a liquid conduit connecting to and communicating with the inlet valve; a gas conduit connecting to and communicating with the inlet valve; an inlet valve control for rotating the inlet valve into two positions, the first position placing the liquid conduit in communication with the inlet port, and the second position placing the gas conduit in communication with the inlet port; a discharge valve connecting and communicating with the chamber through an outlet port located at a higher of said levels of the chamber; a discharge conduit connecting and communicating with the discharge valve and having a discharge outlet disposed lower than the lowest of said levels of the chamber; a draining conduit connecting and communicating with the discharge valve disposed within the chamber and having a draining port located at a lower level of the chamber, said draining conduit passing through the shell at a higher of said levels of the chamber; a discharge valve control for rotating the discharge valve into three positions, the first position placing only the drawing port in communication with the discharge conduit, the second position placing only the outlet port in communication, and the third position placing the discharge conduit in communication with the chamber through both the outlet port and draining port.

3. An apparatus having a cored shell with the cored section describing a chamber having a generally semi-annular configuration with its midportion disposed at a lower level than its two apexes and with its two apexes disposed upward comprising: an inlet valve connecting and communicating with the chamber at an inlet port located at its first apex; a liquid conduit connecting to and communicating with the inlet valve; a gas conduit connecting to and communicating with the inlet valve; an inlet valve control for rotating the inlet valve into two positions, the first position placing the liquid conduit in communication with the chamber at said inlet port, and the second position placing the gas conduit in communication with the chamber at said inlet port; a discharge valve connecting and communicating with the chamber at an outlet port located at its second apex; a discharge conduit connecting and communicating with the discharge

valve; a syphoning conduit connecting and communicating with the discharge valve disposed within the chamber and having a draining port located at said lower level of the chamber; a discharge valve control for rotating the discharge valve into three positions, the first position placing only the draining port in communication with the discharge conduit, the second position placing only the outlet port in communication with the discharge conduit and the third position placing the discharge conduit in communication with the chamber through both the outlet port and draining port.

4. A trunnion bearing cooling apparatus having a cored bearing shell for supporting a trunnion with the cored section describing a chamber having a generally semi-annular configuration with its midportion disposed at a lower level than its two apexes and with its two apexes disposed upward comprising: a three way inlet valve having three ports connecting and communicating from its first port with the chamber through an inlet conduit having an inlet port located at the first apex communicating with the chamber; a cooling liquid conduit connecting to and communicating with the inlet valve at its second port; a gas conduit connecting to and communicating with the inlet valve at its third port; an inlet valve control for rotating the inlet valve into two positions, the first position forming a cooling liquid inlet means by placing the cooling liquid conduit, inlet valve, inlet conduit, and inlet port in communication with the chamber, and the second position forming a gas flow means by placing the gas conduit, inlet valve, inlet conduit, and inlet port in communication with the chamber; a three way discharge valve having three ports connecting and communicating from its first port with the chamber through an outlet conduit having an outlet port located at the second apex communicating with the chamber; a discharge conduit connecting and communicating with the discharge valve at its second port at one end and having a discharge outlet, disposed lower than the midportion of the chamber, at the other end; a draining conduit disposed within the chamber connecting and communicating with the discharge valve at its third port and having a draining port located at a lower level of the chamber, said draining conduit passing through the shell at the second apex and communicating between the chamber at a lower level and the discharge valve; a discharge valve controlling means for rotating the discharge valve into three positions, the first position placing the discharge outlet in communication with the chamber through the discharge valve, outlet conduit, and outlet port, the second position placing the discharge outlet in communication with the chamber through the discharge valve, draining conduit, and draining port, and the third position placing the discharge outlet in communication with the chamber through the discharge valve, outlet conduit, outlet port, draining conduit, and draining port.
